GRAIN CAR DOOR.

APPLICATION FILED MAY 9, 1907.

2 SHEETS—SHEET 2.

UNITED STATES PATENT OFFICE.

JACOB THOMPSON, OF GARRETSON, SOUTH DAKOTA, ASSIGNOR OF ONE-HALF TO GEORGE F. ROSE, OF COLORADO SPRINGS, COLORADO

GRAIN-CAR DOOR.

No. 897,678.

Specification of Letters Patent.

Patented Sept. 1, 1908.

Application filed May 9, 1907. Serial No. 372,756.

To all whom it may concern:

Be it known that I, JACOB THOMPSON, a citizen of the United States, and a resident of Garretson, in the county of Minnehaha and 5 State of South Dakota, have invented a new and Improved Grain-Car Door, of which the following is a full, clear, and exact description.

This invention relates to certain improvements in inner doors for box cars and especially for those cars used for shipping grain and more in particular involves improvements in a door whereby grain may be shipped without danger of leakage such as would occur around the door of an ordinary 10 freight car and whereby time and expense in opening the door may be saved.

The invention comprises two sliding doors preferably of steel sliding within steel casings on the inner side of the car and so constructed 20 that when the doors are not being used they may be moved along steel tracks out of the way and effectively concealed within the casing.

Reference is to be had to the accompanying 25 drawings forming a part of this specification, in which similar characters of reference indicate corresponding parts in all the figures in which

Figure 1 is a side elevation of a car 30 equipped with my improved inner door and having the customary outer door on the outside; Fig. 2 is a plan of the car with a portion of the roof removed to more clearly disclose my improvements; Fig. 3 is a front elevation of my improved doors taken on the line 3—3 of Fig. 4; Fig. 4 is a horizontal section on the line 4—4 of Fig. 3 and enlarged to the same scale as Fig. 3; and Fig. 5 is a vertical section through the doorway, showing the 40 inner doors open.

My improved grain car door is capable of being applied to any ordinary freight car and may be completely removed from the car without leaving the latter disfigured or injured in 45 any way.

My improvements involve two casings 6, located on the inner wall of the car and on the opposite sides of the main car entrance, and these casings are of sufficient width and 50 depth to receive my improved inner doors 7, arranged to slide on tracks 8 into these casings. The doors 7 are of simple construction and are of sufficient strength to withstand the pressure of a load of grain when applied 55 against them from the inner side. Each of

the doors 7 has a groove cut in the under side and extending throughout the entire length of the door and upon the inner surface of which there are preferably provided a plurality of anti-friction rollers 9. The groove 60 in the lower edge of each of the doors fits on an upwardly-extending flange on the track 8 and the door may be easily moved into the casing or out in its operative position along this track. One of the doors is preferably 65 provided with a groove 10, along its outer vertical edge, into which the baffle 11 of the opposite door fits when the two are brought together in the position shown in Fig. 1. This serves to hold the doors in perfect alignment, as does also the track, with its flange 70 extending up into the groove in the bottom of the door.

To rigidly hold the doors at their upper ends when in a closed position and to prevent any accidental opening of the doors to permit of the escape of the grain, I provide a locking means comprising a channel-shaped member having downwardly-extending flanges 12 and 13, and spaced apart by 75 so a web 14, which latter is substantially as wide as the door is thick, so that when the doors are closed the channel may be dropped downward on the top of the two doors and serve to hold their upper ends in alignment. 80 The front flange 12 is preferably provided with holes 15 coinciding with similar holes in the upper edge of the door, and the channel member carries two or more pins 16, which may be inserted through the corresponding 85 holes 15 of the flange and of the doors to hold them in their closed position. These pins may, if desired, be secured to the channel member by short chains, so that there is no danger of the pins becoming accidentally displaced or lost. Before opening the doors the pins 16 must, of course, be removed although 90 the channel is preferably left in place until the grain or other commodity pressing against the door on the inner side be removed. The channel is then raised free from the doors and supported upon hooks 17 on the inner wall of the car near the roof and above the door opening, so that this channel member will be entirely out of the way and 95 one may freely enter the door opening. The ends of the channel member are preferably secured to the inner wall of the car by short chains 18 of sufficient length to permit of the channel being secured to the top of the slid- 100

ing doors, or to permit of its being raised and supported on the hooks 17, the chains serving to prevent the accidental displacement or the mischievous removal of the channel 5 locking member.

In order that the entrance to the door may be perfectly unobstructed when the small sliding doors are removed back into their casings, I preferably make the track of two 10 sections, each of which is hinged at the point 19 just inside its corresponding casing and which may be moved on said hinge into the vertical position shown in dotted lines in Fig. 3 and in full lines in Fig. 5. The ends 15 of these two track sections may, if desired, be cut at an angle or one of them provided with a groove and the other with a corresponding flange, so that the tracks will always be in alinement when resting upon the 20 floor of a car, as shown in Fig. 4.

When the car is loaded with grain and it is desired to unload the same it is often found that it is practically impossible to move the inner door unless some special means be provided, as the pressure of the grain against 25 the side of a car causes it to bind against the track and floor of the car. To overcome this, I provide a pipe 20, extending from one of the casings 6 to the end of the door in the 30 car and through this extends a chain or cord 21 having one end thereof rigidly secured to the adjacent door, and having the other end extending to a drum 22 located on the outer end of the car. Any suitable means for rot- 35 ating this drum may be provided, as for instance, a lever 23 and pawl and ratchet 24. By rotating the drum the chain is withdrawn from the car and one of the sliding doors is drawn back into its casing and the grain 40 may then be removed. If desired, both of the inner sliding doors may be provided with this means for opening them but usually one will be sufficient, for as soon as one of the doors is opened in this way, pressure may be 45 brought directly against the edge of the opposite door and it may be opened without very much trouble.

As the doors when opened are moved back into the casings beyond the front edges thereof 50 and the track sections are swung up into the casings to effectively conceal the front edges of the doors, it is often difficult to obtain a secure enough hold upon the door to pull it out of its casing in order to close the 55 same. To obviate this difficulty, I provide each door with a sliding strip 25 secured thereto in any suitable manner but preferably by a screw-bolt 26 passing through a slot 27 in the strip. The strip is secured to 60 the countersunk panel portion of the door and its outer edge lies flush with the edge of the door, but the door frame is cut away to permit of its passage and prevent it from projecting beyond the surface of the door. The 65 outer end of each strip is provided with a

hook or catch 28 adapted to abut against the door casing, and as the door is drawn or pushed back into its casing the hook 28 prevents the strip from passing in more than a certain predetermined distance. The horizontal flange of the track 8 is provided with a notch or cutaway portion 29 to permit of the resting of the track in a vertical position while the strip 25 still extends out from the protecting casing of the door. The ends of 70 the strips at the hooks 28 may be provided with any suitable form of handle, so that after the track has been dropped down to its horizontal position, the door may be pulled out by means of this handle and the strip 25. 75 A suitable pin or other means 30 may be employed for holding the track in its vertical position when the car is being unloaded or when it is not employed for the shipment of grain. 80

The car has the customary outer sliding door 31, fitting in grooves 32 and 33 at the bottom and top, respectively, and as a lock may be applied to this door it is unnecessary to lock the inner door. Furthermore, the inner door preferably does not extend as high as the outer door for it is not customary to load the grain cars to the very roof thereof. The threshold of the door is preferably 85 formed of a steel plate 34, to prevent the car floor from wearing away at this portion, thus causing the track to fit the car floor unevenly and permitting the escape of grain beneath the said track.

When the car is loaded with grain all the 100 parts are in the position shown in Fig. 1, and when it is desired to unload the car, the pins 16 are withdrawn and the channel bar raised up to its position beneath the roof of the car and supported on the hooks 17. One of the 105 doors is then opened by means of the lever 23, then the other door may be easily opened and the two track sections, when secured in place by the pins 30, raised to their vertical position shown in Fig. 5.

Having thus described my invention, I 110 claim as new and desire to secure by Letters Patent:

1. A car having two laterally sliding doors movable from and toward each other, a detachable channel member adapted to inclose the upper edges of the doors, and means for locking the doors to said channel when they are in their closed position.

2. A car having two slidable doors in alinement with each other and having their adjacent edges in engagement with each other when the doors are in their closed position, a detachable channel member adapted to fit over the upper edges of the doors when they are in the last-mentioned position, and means carried by said channel member for preventing the separation of said doors, when they are in their closed position.

3. A car having two doors, the vertical ad- 130

jacent edges of which are in engagement with each other when the doors are in their closed position, a channel member adapted to be placed over the upper horizontal edges of said doors when in their closed position, and means for securing the channel to said doors, to normally prevent their being opened.

4. A car having two inner sliding doors, casings for receiving said doors when the latter are in their open position, and tracks upon which said doors slide, said tracks being hinged and adapted to be swung up into said casing to protect the edges of the doors when the latter are opened.

15 5. A car, comprising two inner sliding doors, casings inclosing said doors, hinged track sections adapted to be swung on their hinges into said casings when the doors are opened, and means for holding said track

20 sections within said casings.

6. A car having an opening in one wall thereof, a door slidably mounted to close said opening, a casing inclosing said door when in its open position, and a track upon 25 which said door may slide, said track being hinged adjacent the edge of the car opening and movable to a position adjacent the front edge of the door when the latter is in its open position and serving to close the front side of 30 the casing.

7. A car having a doorway in one wall thereof, a slideable door for closing said doorway, a strip secured to said door and slideable in relation thereto and in the direction of 35 movement of said door, said strip having a projection adapted to engage with the car wall at the edge of the doorway and serving

as means whereby the door may be drawn to a closed position in front of said doorway, and a track upon which said door may slide, 40 said track having a section hinged adjacent the edge of the doorway movable to a position adjacent the front edge of said door and having an opening for the reception of the end of said strip.

45 8. A car having a doorway in one wall thereof, a slideable door for closing said doorway, means extending beyond the edge of the doorway when the door is in its open position for facilitating the closing of said door, 50 and a track upon which said door may slide, said track having a section hinged adjacent the edge of the doorway and movable to a position adjacent the front edge of the door, said section having an opening for the reception of said means.

9. A car, comprising two slideable doors, strips secured to each of said doors movable in relation thereto, hooks on the ends of said strips adapted to engage with the car wall 60 and by which the doors may be closed, hinged track sections upon which said doors slide, and means whereby said track sections may be moved to a vertical position, said track sections being provided with cutaway 65 portions to receive the hooks on said strips.

In testimony whereof I have signed my name to this specification in the presence of two subscribing witnesses.

JACOB THOMPSON.
